US0D1107034S

(12) **United States Design Patent** (10) Patent No.: **US D1,107,034 S**
Zhong (45) Date of Patent: ** Dec. 23, 2025

(54) **DISPLAY SCREEN OR PORTION THEREOF WITH A GRAPHICAL USER INTERFACE**

(71) Applicant: **Strategy Inc**, Tysons Corner, VA (US)

(72) Inventor: **Xiaodi Zhong**, Hangzhou (CN)

(73) Assignee: **Strategy Inc**, Tysons Corner, VA (US)

(**) Term: **15 Years**

(21) Appl. No.: **29/871,309**

(22) Filed: **Feb. 16, 2023**

(51) LOC (15) Cl. **14-04**

(52) U.S. Cl.

USPC **D14/485**

(57) **CLAIM**

The ornamental design for a display screen or portion thereof with a graphical user interface, as shown and described.

DESCRIPTION

The FIGURE is a front view of a display screen or a portion thereof with a graphical user interface showing our new design.

The broken lines showing the display screen or a portion thereof form no part of the claimed design. The remaining broken lines showing portions of the graphical user interface form no part of the claimed design.

1 Claim, 1 Drawing Sheet
